OVEN DOORS

Montgomery Ferar, Detroit, Mich., assignor to
Florence Stove Company, Gardner, Mass., a cor-
poration of Massachusetts

Application April 11, 1947, Serial No. 138,319

Term of patent 7 years

(Cl. D81—25)

To all whom it may concern:

Be it known that I, Montgomery Ferar, a citizen of the United States, residing at Detroit, in the county of Wayne and State of Michigan, have invented a new, original, and ornamental Design for a Handle for Cookstove Oven Doors, of which the following is a specification, reference being had to the accompanying drawing forming a part thereof.

Figure 1 is a plan view of a handle for cookstove oven doors showing my new design.

Fig. 2 is a front elevational view of the handle.
Fig. 3 is an end view.

Fig. 4 is a transverse sectional view taken approximately in the plane of line 4—4 of Fig. 2.

I claim:

The ornamental design for a handle for cookstove oven doors, substantially as shown.

MONTGOMERY FERAR.
